SLUB DETECTOR, CATCHER, OR BREAKER

Application filed September 29, 1930. Serial No. 484,993.

This invention relates to devices for detecting imperfections, in the nature of enlargements, in textile strands including spun yarns, threads, and cordage, as well as wire, 5 or other filaments, hereinafter generically referred to for convenience as "yarn". Such a device may exercise a controlling action with respect to the functioning of any element which is to be affected by or in response to 10 the presence of an enlarged abnormality on the yarn. Specific illustrations of such functioning are the motion of the yarn itself, the movement of a valve, or the tripping of a trigger.

15 The invention will be described, for purposes of illustration, and not by way of limitation, as embodied in a detector for detecting those enlarged imperfections on yarn which are commonly known as "slubs". Such 20 slub detecting mechanism may be applied to any moving strand of yarn to detect slubs thereon, and specific instances of its applicability are to a winding machine of any kind, to a device for inspecting yarn, and to 25 a yarn-using machine, such, for example, as a continuous weft loom, braiding machine or knitting machine, to detect slubs which ought not to be permitted to enter these machines.

I have found it desirable to detect the presence 30 of soft slubs which are relatively large in diameter and to ignore the presence in the yarn of such imperfections as are usually termed "nips". In weaving certain types of fabrics small imperfections in the yarn such 35 as nips or neps are allowable, and one object of this invention is to provide a detector which will not be caused to function by these permissible imperfections, but which will respond to slubs of large diameter or which are 40 of substantial length, or, more specifically stated, to provide detecting means which will be caused to function whenever a slub or imperfection of more than a certain thickness passes therethrough, or whenever a slub of 45 less than this thickness but having a certain length passes therethrough. Stated differently, an object of the invention is to provide detecting means which is responsive in its 50 operation to a function of both the diameter and length of an imperfection, for example,

the volume. It will be understood that a slub is not truly spherical in shape but is elongated in the direction of length of the yarn, and that its bulk is a function of both its length and diameter.

A further object of the invention is to provide improved detecting means which is readily adjustable to allow thicker imperfections to pass without detection when larger yarn is being inspected. In determining the 55 maximum size of a slub which is to pass without causing the detector to operate, I have found it desirable to consider the relation between the length of the slub and the size of the yarn, and in some instances to 60 allow not only a thicker, but also a longer slub, to pass the detector without actuation thereof, when larger yarn is being inspected. Accordingly, another object of the invention is to render the detector simultaneously adjustable for size of yarn, and for length as 65 well as diameter of imperfections which will pass the detector without causing the detector to operate.

In the accompanying drawings:

Fig. 1 is a plan view of slub detecting means typical of the invention;

Fig. 2 is a section on line 2-2 of Fig. 1, showing the movable detector or feeler in its normal position;

Fig. 3 is a fragmentary view corresponding to Fig. 2 but showing the movable slub-engaging detector in the position to which it has been moved by a slub on the yarn, and which may be called the detecting position;

Fig. 4 is a section on line 4-4 of Fig. 2;

Fig. 5 is a perspective view of a shim adapted for use in the movable slub-engaging means;

Fig. 6 is an illustration of a small eccentric nip on the yarn which the slub detector is adapted to allow to pass without being actuated thereby;

Fig. 7 is an illustration of a large, soft slub which will actuate the detector;

Fig. 8 is a front elevation of a detector embodying the principle of the invention but in modified form;

Fig. 9 is a plan view of the detector of Fig. 8;

Fig. 10 is a view similar to Fig. 8 but showing the detector after movement by engagement in an enlargement on the yarn;

Fig. 13 is a diagram illustrating the principle of operation of the detector of Fig. 8; and

Fig. 14 is a perspective view of another embodiment of the invention adapted to break the yarn upon the occurrence of a long soft slab, as distinguished from a short permissible imperfection.

The slab detecting mechanism is adapted to operate in response to the relative movement of a yarn and the detector mechanism as a whole, and when I refer to the "passing" yarn I wish the expression to be understood in the relative sense, although it is true that in most cases the yarn is in reality the moving element. In the present embodiment of the invention the strand of yarn Y is drawn through suitable guiding means by the tractive effort of any suitable yarn-using or winding machine. In the embodiment illustrated in Figs. 1 and 2, the yarn guiding means comprises porcelain knobs 2 and 3, guide pins 4 and 5, and a yoke 6. These latter guiding members are carried by a fixed arm 7, to which the porcelain knob 2 is attached by means of the pivoted extension arm 8. The yoke 6 is rigidly secured at one end to the arm 7 and at the other end to a block 9 which may be supported in any suitable manner in the yarn winding, inspecting, or using machine with which the slab detecting mechanism is to be used.

The slab responsive means comprises a movable feeler or detector adapted to allow certain permissible imperfections, such for example, as the nip N of Fig. 6, to pass freely therethrough, but which is adapted to be moved by frictional contact with long soft slabs. In order to prevent the slab-engaging detector or feeler from being actuated by nips, I provide the detector with slab-engaging surfaces spaced sufficiently far apart to permit these nips to pass therebetween with but slight frictional resistance, but of sufficient length in the direction of the travel of the yarn to offer considerable frictional resistance to the passage of long soft slabs.

A slab is soft and easily compressible, and I have found it desirable to utilize these characteristics in bringing about a frictional contact between the moving slab and a movable slab-engaging detector or feeler, and in distinguishing between slabs and permissible imperfections. Accordingly, I space the slab-engaging surfaces of the detector sufficiently close to exert a substantial compressing action upon large and undesirable slabs.

In this compressed condition the large slabs

exert a much greater frictional pull on the detector than the denser and harder nips, since the former are considerably compressed and the latter are not. By this compressive action imperfections in the yarn are progressively reduced to a certain maximum thickness (equal to the distance between the slab-engaging surfaces), and the forward motion of those imperfections which are under compression and have considerable surface area, namely, large or long slabs, is utilized to actuate the slab detector. The movable slab detectors or feelers employed in the specific embodiments of the invention described herein are examples of structures having this mode of operation, and it will be understood that these examples are illustrative of a class of structures which might be employed.

The movable slab-engaging element (Fig. 4) comprises spaced plate members 10 and 11, defining between them a yarn-receiving throat 26, and connected by a stud bolt 12. In the detector herein described, the function of guiding a strand of yarn into the yarn-receiving throat 26 is performed by the out-turned portions 13 and 14, which are integral with, but of less height than members 10 and 11. Members 10 and 11 have a considerable dimension in the direction of motion of the yarn, shown in Fig. 2 as of several times (preferably say 16 to 50 times) the width of the throat 26. For specific example, in the case of certain yarns, the members 10 and 11 may be spaced from five to thirty thousandths of an inch apart while having a dimension in the direction of movement of the yarn of one-half inch. A normal setting of the members 10 and 11 may be about .015 inches apart, or but slightly greater than a common average diameter of eccentric nips. Due to their relatively large dimension in the direction of the travel of the yarn, members 10 and 11 present surfaces of relatively large area between which the yarn is passed.

The throat 26, as shown in Fig. 4, has a lateral depth of several times (and preferably many times) its width. This depth of throat 26 permits a strand of yarn to run freely therethrough and permits a small nip N which usually protrudes eccentrically of the yarn to twist its longer dimension into the direction of depth of the throat and thus pass freely through, instead of being wedged between the two side surfaces thereof.

The yoke 6 and guide pin 5 align the yarn with the throat 26 and also retain the yarn in a position (Figs. 2 and 3) in which imperfections can not engage or wedge in the right-hand end, which I call the "bottom", of the throat. This prevents a positive actuation of the slab-engaging element by a small nip wedging in the bottom of the throat.

In some cases I provide means for rendering the detector adjustable for various sizes

of yarn and for determining the thickness of a slab which will actuate the device. In the embodiment of the invention shown in Figs. 1 to 4, I have provided such an adjusting means in the form of a removable shim or shims 15 held in place by the bolt 12 and adapted to determine the spacing of members 10 and 11 and the width of the throat 26. 5

I may also, if desired, provide means for 10 adjusting the inertia of the detector, and in the embodiment of Fig. 4 this function is performed by the same adjusting means that is employed to determine the width of throat 26, namely a shim or shims 15. To adjust 15 the slab-engaging element to adapt it for use with larger yarn, a thicker shim 15 is inserted or an additional shim 15 is added, and hence the space between members 10 and 11 is increased and the inertia of the slab- 20 engaging element increased simultaneously. This duplexity of function of the shim or shims 15 constitutes a distinct advantage in that an increase in thickness of the shim or shims 15 to adapt the slab-engaging means 25 for use with larger yarns simultaneously increases the inertia of the slab-engaging means. The desirable result of presenting greater resistance to slabs on larger yarn than on smaller yarn is accomplished, and 30 more massive slabs may thus be permitted to pass without actuation of the slab-engaging means when larger yarn is inspected. 35

The slab-engaging detector or feeler comprising members 10 and 11 is adapted to implement motion to some other element, which in the embodiment of the invention illustrated herewith is a shaft 17, mounted for rotation in block 9, and adapted to perform any desired indicating or controlling function such, 40 for example, as tripping a trigger, moving a valve, operating a yarn cutting shear, etc. A member 10 of the slab-engaging means is rigidly connected to a collar 18 which in turn is keyed or otherwise fastened at 19 to the 45 rotatable shaft 17. In this manner, the slab-engaging means is mounted for rotation from the position shown in Fig. 2 to that of Fig. 3, and motion of the slab-engaging means is transmitted to shaft 17. The particular apparatus controlled by shaft 17 50 forms no part of this invention, and hence will not be described.

In operation, the yarn passes over the guiding means comprising knobs 2 and 3, arms 55 4 and 5, and through yoke 6 in the direction of the arrow, as shown in Fig. 2, passing through throat 26 between members 10 and 11 of the detector. The detector has considerable inertia and is not moved by frictional contact of the yarn therewith. A 60 small nip N, as shown in Fig. 6, will pass between the surfaces 10 and 11 of the detector without exerting sufficient frictional contact with the inner surfaces of its throat 65 to cause actuation thereof. When, however, a long, soft slab, such as is shown at S in Fig. 7, engages the throat of the detector, it is compressed thereby and the frictional engagement between the slab and the walls 10 and 11 of the throat is sufficient to enable the forward motion of the slab to carry the detector through an arc from the position of Fig. 2 to the detecting position of Fig. 3, thereby rotating shaft 17 and causing it to exercise the desired indicating or controlling function. As shown in Fig. 3, when the slab has rotated the slab-engaging element through a certain arc, the component of the movement of the detector perpendicular to the yarn has become great enough to disengage the narrow portion of the throat from the slab and allow the slab to pass freely upward between the out-turned members 13 and 14. The detector is restored to its normal position, as shown in Fig. 2, by gravity, 70 subsequent to the passage of the slab, or by any suitable mechanism for manually or automatically restoring it to its normal position. The restoring force acting on the movable portion of the detector, as the result of gravity in the illustrated embodiments, is an important factor in the operation of the detector to distinguish between yarn imperfections of different lengths. This restoring force, adjusted to a suitable magnitude by the mass of the moving parts, is effective to resist movement of the detector upon the lesser frictional drag of a short permissible imperfection, but is adapted to yield to the greater frictional drag set up by a long slab. 75 This restoring force acting on the movable portion of the detector constitutes a force against which the frictional drag of the various yarn imperfections can be measured or compared one at a time so that the movement or non-movement of the detecting element is determined by the characteristics of the individual imperfections severally with the avoidance of cumulative effect caused by the successive occurrence of slight imperfections which in the absence of such restoring force will tend to move the detector to its 80 detecting position. 85

In passing through the throat 26 of the described detector, a soft slab is considerably compressed but the yarn is not broken. The amount of force frictionally transmitted by the slab to the detector depends both upon the thickness and the length of the slab. A slab that is relatively small in diameter but of considerable length will impart sufficient force to the detector to rotate the latter, while a small hard nip, or a short slab of less than a predetermined thickness, will pass through the throat without frictionally imparting sufficient force to overcome the inertia of the detector and hence will not cause the latter to move to its detecting position. 90

If the detector is adjusted for use with a larger size of yarn by inserting a larger shim 95

or a greater number of shims, the throat will accordingly be widened and will allow thicker imperfections to pass therethrough without actuation, since when the thickness of shim 15 has been increased or the number of shims has been increased, the mass and inertia of the detector are likewise increased. Therefore a greater force must be imparted to the detector by an imperfection in the 10 yarn, or a force applied for a greater length of time, in order to overcome the increased inertia of the detecting means and cause an actuation thereof. This permits not only a thicker but also a longer slab to pass through 15 the throat of the detector without actuation thereof.

In order, when desired, to cause the slab-engaging means to transmit motion to shaft 17 in the absence of a slab or imperfection, 20 and also to enable the detector to be moved out of the path of the yarn when desired, I have provided means other than the slab-laden yarn for moving the slab-engaging means. In the embodiment of the invention 25 illustrated herewith, this means for moving the slab-engaging means or detector comprises a lever 20 pivoted to block 9 by a bolt 21, and provided with a flattened portion 22 adapted to be engaged by the finger of an operator. Arm 20 extends underneath members 10 and 11 of the detector and by depressing the flattened portion 22 of the lever 20, the slab-engaging means and shaft 17 can be moved an amount corresponding to 30 the movement caused by the presence of a slab, or farther completely to remove the slab-engaging means from the path of the yarn. In order, when desired, to maintain the slab-engaging means in an elevated position, means is provided for frictionally 35 maintaining lever 20 in whatever position it is placed, for example by the provision of a small spring 23 which is engaged by the bolt 21 frictionally to hold the lever 20 against the block 9.

Figs. 8 to 13 inclusive illustrate a modified arrangement wherein the throat or passage through which the yarn moves is automatically constricted as soon as the detector 50 is moved from its normal position by engagement with an enlargement or slab on the yarn. This arrangement is even more certain in its operation than that described above in dealing with very soft slabs, since the 55 instant the detector as a whole begins to move in response to the frictional action of the slab the opposite sides of the throat begin to approach, thus placing the slab under greater compression and thereby increasing the friction so that even the softest slab acts with certainty to move the detector to its limited position. By reason of the gripping action of this form of detector it 60 may be used as a direct means for breaking the 65 yarn, although I contemplate that it

will be used in the same way as the detector of Fig. 1 for actuating some other part, either near or remote, for example, a yarn cutting shear or a stop motion for the yarn delivery means.

In this modified construction the detector elements 10^a and 11^a (Fig. 9) with their diverging guide elements 13^a and 14^a respectively may be and preferably are similar to the elements 10 and 11 above described, normally being spaced to define between them a throat 26^a for the passage of the yarn. As above described, this throat preferably is of much greater dimensions in the direction of movement of the yarn than transversely of the yarn so as to permit small, hard enlargements to pass while responding to the frictional drag of long, soft slabs. As indicated in Fig. 8, the yarn may, if desired, first pass through suitable tensioning devices, indicated at T, then through the throat 26^a and then between suitable guides G.

As illustrated more clearly in Fig. 9, the detector elements proper 10^a and 11^a are carried by supporting arms 10^b and 11^b, the arms with their respective detector elements preferably being integral and consisting of pieces of thin sheet metal each having portions which are bent at an angle, preferably a right angle to each other, to form the detector elements 10^a and 11^a. The arms 10^b and 11^b are disposed closely adjacent to one another, the arm 11^b being in front and the arm 10^b at the rear. Preferably as shown in Fig. 9, the rear arm 10^b is provided with a portion 10^c bent away from the arm 11^b to form an enlarged open-bottomed pocket or slot 10^d capable of receiving lint which might otherwise clog the throat of the detector. As indicated more clearly in Figs. 11 and 12, the arm 10^b is provided with an opening 30 which receives a pivot member, for example, a shaft 17^a, corresponding to shaft 17 of Fig. 2 and adapted by its partial rotation to actuate or set into operation any desired part or mechanism. As indicated in Fig. 12, the opening 30 is near the lower right-hand corner of the arm 10^b, the opening 30 being of substantially the same diameter as the pivot member so that the arm 10^b swings in a definite arcuate path, the arm being fixed to shaft 17^a if the latter is to be actuated by movement of the arm. The arm 11^b is provided with a pivot opening 34 near its upper right-hand corner which receives a pivot pin 35 of substantially the same diameter as the opening. The arm 11^b also has an opening 33 directly below the opening 34 of a diameter substantially larger than that of the pivot member 17^a through which the latter passes freely. Likewise the arm 10^b has an opening 36 directly above the opening 30 for the passage of the pivot pin 35, but this opening 36 is of considerably larger diameter than 120 125 130

- the pin 35. The arms 10^b and 11^b are thus free to swing independently about their respective pivots to a limited extent. Preferably the arm 10^b has an elongate slot 38 which receives a pin 37 projecting rearwardly from the arm 11^b. The pivot member 17^a and the pivot pin 35 are received in holes in a block 9^a, corresponding to the block 9 of Fig. 2.
- 10 The principle of operation of this construction is illustrated in Fig. 13 where, to a large scale, detector elements D and D¹ are carried respectively by the arms A and A¹ pivoted at P and P¹ respectively. The arms D and D¹ define between them the throat or passage V, shown of exaggerated width in this figure, and it will be noted that when the arms A and A¹ are swung to the dotted line position, the detector elements D and D¹ 15 move toward each other so that the throat comes narrower as shown at V'.
- 15 Referring again to Figs. 8 and 10, the yarn Y is shown in Fig. 8 as passing through the normally disposed detector device having the throat 26^a open for the passage of the yarn. However, when the slub S on the yarn enters between the detector elements 10^a and 11^a, it is slightly compressed and begins to move these elements with their supporting 20 arms upwardly, it being noted that in this construction the detector elements with their arms may be extremely thin and light. As soon as the arms begin to move up the detector elements approach so that, as shown in Fig. 25 10, the throat 26^a has become very narrow so that the slub can not pass, thus positively completing the upward movement of the detector elements and breaking the yarn if the movement of the yarn is continued.
- 30 40 Obviously by varying the lengths of the supporting arms and the spacing of the pivots for the arms as well as the arrangement of the stop means, the detector may be caused to function in response to slubs of different sizes and character.
- 45 In certain of the appended claims where it is stated that the slub-engaging means is not actuated by certain imperfections on the yarn, it is meant that the slub-engaging 50 means or detector is not moved completely to its detecting position. Rapidly passing yarn having permissible imperfections may operate ballistically upon the slub-engaging means, but will fail to move it to its full detecting position as would a long soft slub.
- 55 The distance between the opposed blades of the various forms of my invention should be such that permissible imperfections, such as nips, will pass freely into the throat defined by the blades, and so that the longer objectionable imperfections of about the same diameter will also pass into this throat. This arrangement insures that the yarn will not, in general, be broken by permissible imperfections striking the entrance to the throat as
- in the case of devices which rely upon the inability of imperfections to enter a restricted throat or similar opening. The devices of the present invention differ from such prior devices by providing a throat of such depth 70 in the direction of yarn travel as to grip or retard yarn imperfections which have been pulled into the throat. As explained above in connection with the other forms of the invention, the small surface area of the permissible imperfections, such as nips, permits these imperfections to pass through the throat without exerting sufficient drag to cause breakage of the yarn.
- 75 It should be understood that the present disclosure is for the purpose of illustration only and that this invention includes all modifications and equivalents which fall within the scope of the appended claims.
- 80 I claim:
1. Slub detecting mechanism comprising a pair of detector elements, each having a yarn-engaging part and a supporting arm disposed substantially at right angles to the yarn-engaging parts of the two elements being normally parallel and spaced to provide a throat for the passage of the yarn, a pivot for one arm, the other arm having an opening through which said pivot loosely passes, stop means limiting movement of the arms, said stop means being arranged to permit greater pivotal movement of the pivoted arm than of the other arm, the pivoted arm having an elongate slot therein and a pin projecting from the other arm into said slot. 90
- 95 2. Slub detecting mechanism comprising a pair of flat blade-like members having substantially parallel detector portions normally spaced to provide a throat for passage of yarn and having supporting portions at right angles to said detector portions, said supporting portions being disposed in superposed relation, pivot means for one at least of said supporting portions, pin and slot connections between said supporting portions, and stop means limiting relative movement of said supporting portions, said detector portions when engaged by a slub on the yarn moving toward each other and thereby constricting the throat. 100
- 105 3. Slub detecting mechanism comprising a pair of flat blade-like members arranged one in front of the other and constituting supporting arms, said members having portions disposed at right angles thereto to form normally parallel detector elements, said elements being spaced to provide a throat for the passage of yarn, a pivotal support for the rear arm constraining it to move in a defined arcuate path, the front arm having an opening through which said pivotal support passes loosely, the front arm having the second opening above the first, a pivot pin passing through said second opening, the rear arm having an opening of larger diameter for 110
- 115 120
- 125 130

passage of said pin, and a pin projecting from the front arm into an elongate slot in the rear arm.

4. Slub detecting mechanism comprising a pair of flat blade-like members arranged one in front of the other and constituting supporting arms, said members having portions disposed at right angles thereto to form normally parallel detector elements, said elements being spaced to provide a throat for the passage of yarn, independent pivots for the respective arms whereby they are adapted to swing in different arcuate paths, and means for limiting such movement.
5. A slub detector comprising opposed throat-defining plane portions parallel at least during inaction and spaced to permit the passage of yarn therebetween and at a sufficient distance to permit yarn imperfections to pass within the throat in frictional engagement therewith, said throat-defining portions extending sufficiently far in the direction of yarn travel to grip the yarn imperfection contained in said throat much more firmly in the case of a long slub than in the case of a short imperfection of comparable diameter, and means for mounting at least one of the said throat-defining plane portions for movement in the same direction as the traveling yarn against a restoring force of magnitude effective to prevent such movement in the case of short permissible imperfections and adapted to be overcome by the friction of a long slub.
6. A movable slub-engaging detector element comprising two members defining a yarn-receiving throat therebetween, means for mounting said element for motion with a traveling strand upon the frictional engagement of a slub between the said members, a removable shim and means for retaining said removable shim between said members, whereby the inertia to such motion may be adjusted by the substitution of a shim of the requisite mass.
7. A movable slub-engaging element mounted for movement with the traveling yarn and provided with a yarn receiving throat, and means for simultaneously adjusting the width of said throat and the inertia of said slub-engaging element.
8. A movable slub-engaging element provided with spaced slub-engaging surfaces defining a throat through which yarn is adapted to pass, at least one of said surfaces having a dimension in the direction of the travel of the yarn of at least sixteen times the width of said throat and means for mounting said element for movement with the traveling yarn upon the entry of a slub between said surfaces.
9. A movable slub-engaging element provided with spaced slub-engaging surfaces defining a throat through which yarn is adapted to pass, said surfaces having a dimension

in the direction of the travel of the yarn of at least sixteen times the width of said throat, and means for mounting said element for movement with the traveling yarn upon the entry of a slub between said surfaces.

10. A movable slub-engaging element provided with spaced slub-engaging surfaces defining a throat through which yarn is adapted to pass, said surfaces having a dimension in the direction of the travel of the yarn of several times the width of said throat, the throat having a depth in the direction of yarn travel of at least sixteen times its width, and means for mounting said element for movement with the traveling yarn upon the entry of a slub between said surfaces.

11. A slub detector comprising opposed throat defining plane portions parallel at least during inaction and spaced to permit the passage of yarn therebetween and at a sufficient distance to permit yarn imperfections to pass within the throat in frictional engagement therewith, said throat defining portions extending at least 16 times as far in the direction of yarn travel as compared to the distance between them so as to grip the yarn imperfection contained in said throat much more firmly in the case of a long slub than in the case of a short imperfection of comparable diameter, and means for mounting at least one of the said throat-defining plane portions for movement in the same direction as the traveling yarn against a restoring force of magnitude effective to prevent such movement in the case of short permissible imperfections and adapted to be overcome by the friction of a long slub.

12. A slub detector comprising opposed throat-defining plane portions parallel at least during inaction and spaced to permit the passage of yarn therebetween and at a sufficient distance to permit yarn imperfections to pass within the throat in frictional engagement therewith, said throat defining portions extending sufficiently far in the direction of yarn travel to grip the yarn imperfection contained in said throat much more firmly in the case of a long slub than in the case of a short imperfection of comparable diameter, and means for mounting at least one of the said throat-defining plane portions for movement in the same direction and also out of the path of the traveling yarn against a restoring force of magnitude effective to prevent such movement in the case of short permissible imperfections and adapted to be overcome by the friction of a long slub.

13. A slub detector comprising parallel opposed throat-defining plane portions rigid with respect to each other and spaced to permit the passage of yarn therebetween and at a sufficient distance to permit yarn imperfections to pass within the throat in frictional engagement therewith, said throat defining

portions extending sufficiently far in the direction of yarn travel to grip the yarn imperfection contained in said throat much more firmly in the case of a long slub than in the 5 case of a short imperfection of comparable diameter, and means for mounting at least one of the said throat-defining plane portions for movement in the same direction as the traveling yarn against a restoring force of 10 magnitude effective to prevent such movement in the case of short permissible imperfections and adapted to be overcome by the friction of a long slub.

14. A slub detector comprising opposed 15 throat defining parallel blades spaced to permit the passage of yarn therebetween and at a sufficient distance to permit yarn imperfections to pass within the throat in frictional engagement therewith, said blades 20 which define the throat extending at least 16 times as far in the direction of yarn travel as compared to the distance between them so as to grip the yarn imperfection contained in said throat much more firmly in the case of 25 a long slub than in the case of a short imperfection of comparable diameter, a rotatable shaft, said blades being rigidly fixed with relation to each other and mounted on said shaft to turn against the restoring force 30 of gravity under the lifting influence of passing yarn imperfections, the weight of the thus moving parts of the detector being such that gravity prevents the lifting of the blades in the case of short permissible imperfections 35 while the greater frictional drag of long slubs is adapted to lift the blades and turn said shaft.

15. In a device for detecting slubs, a slub-detecting element mounted for movement 40 with a passing yarn imperfection, means for conveying yarn through said slub-engaging element, an actuating member adapted to move said slub-engaging element independently of the occurrence of a yarn imperfection, 45 said slub engaging element being movable by yarn imperfections independently of said actuating member, and means for retaining said actuating member in a position such as to hold the slub-engaging element 50 out of the path of the yarn.

Signed by me at Melford, New Hampshire
this 25th day of September 1930.

EDWARD J. ABBOTT.
